(74) *Attorney, Agent, or Firm*—Kalow & Springut, LLP;
Scott D. Locke, Esq.

(57) **CLAIM**

The ornamental design for a watch dial, as shown and described.

DESCRIPTION

The sole view is a front elevation of a watch dial showing my new design.

The broken lines in the drawings are used to show portions of the watch dial that do not form part of the claimed design.

1 Claim, 1 Drawing Sheet
